UNITED STATES PATENT OFFICE

152,179

DESIGN FOR A RADIO CABINET

Earl M. Valley, Englewood, Ohio

Application May 3, 1946, Serial No. 129,289

Term of patent 3½ years

(Cl. D56—4)

To all whom it may concern:

Be it known, that I, Earl M. Valley, a citizen of the United States, residing at Englewood, Montgomery County, Ohio, have invented a new, original, and ornamental Design for a Radio Cabinet, of which the following is a specification, reference being had to the accompanying drawing, forming a part thereof, in which Fig. 1 is a perspective view of a radio cabinet, embodying my new design.

Fig. 2 is a front view thereof, and

Fig. 3 is a side view thereof, partly in section showing in detail the particular design of the louvers.

I claim:

The ornamental design for a radio cabinet, substantially as shown.

EARL M. VALLEY.
